PUFFING CEREAL GRAINS

Clifton F. Haughey, Battle Creek, and Reginald T. Erickson, Climax, Mich., assignors to General Foods Corporation, New York, N. Y., a corporation of Delaware

Application January 26, 1951, Serial No. 207,902

13 Claims. (Cl. 99—81)

1

This invention relates to the puffing of cereal grains and more particularly to the production of puffed cereal products of the well known and widely used breakfast food type such as puffed wheat, puffed rice, etc.

According to the general practice of the art for many years, such puffed cereal products have been produced in a so-called "gun" comprising a pressure container in which a batch of the desired grain is heated under steam pressure, after which the container is opened suddenly to release the pressure, causing the grains to be expelled violently therefrom and at the same time to be puffed due to the sudden expansion of their contained moisture in the form of vapor or steam. Under typical operating conditions, each batch may be heated or cooked for from four to eight minutes to a temperature above 500° F. under a steam pressure of about 175 pounds per square inch. Apart from the fact that this procedure has the usual disadvantages of a batch operation, it also produces nonuniform results with respect to the size and other characteristics of the puffed grain. The grains are very sensitive to the time of their exposure to the high temperature and pressure in the gun, to the amount of drop in pressure which they undergo on opening of the gun, and to the rapidity with which this drop in pressure takes place. These conditions can be controlled with respect to the batch as a whole, but it is difficult if not impossible to avoid substantial variations in the treatment of the individual grains of such a batch and especially in the rapidity of the drop in pressure as the grains are being expelled from the gun. Control of these conditions with respect to individual grains becomes more difficult as the sizes of the gun and the batch are increased, whereas on the other hand a large number of small batches is obviously undesirable for quantity production.

It has been proposed to minimize the disadvantages of batch operation by the use of automatic or semi-automatic apparatus in which a plurality of such guns are operated in sequence with overlapping cycles, as for example by charging one gun while another is under steam pressure and while still another is being discharged. However, the apparatus required to effect such operation is complicated and expensive, and in any event the operation of each gun is subject to the above mentioned defects of this method of puffing. In an effort to minimize these defects, it has also been proposed to heat a charge of grain in a pressure container, and then to open a relatively small discharge outlet so that the pressure in the container forces the mass of grain into the outlet and the individual grains of the charge are progressively expelled.

2

In this method, however, the time of exposure of the individual grains to the high temperature and pressure in the container varies substantially because of the time required to expel the entire charge through the restricted outlet, and as a consequence the puffed grains vary not only in size but also in degree of cooking. Moreover, forcing the mass of grain into and through the outlet tends to cause clogging of the outlet with resulting physical distortion and mechanical damage to many of the grains, and with the further result that some grains are held up in passing through the outlet so that the pressure drop therein takes place gradually.

15 One of the objects of the present invention is to provide an improved process for puffing cereal grains which is truly continuous in operation and which produces a uniform product of high quality.

20 Another object is to provide an improved process for puffing cereal grains in which all of the individual grains are subjected to uniform conditions of heating or cooking and pressure drop.

25 Another object is to provide an improved process as characterized in the preceding objects wherein the pressure on and in the individual grains is released with great rapidity.

30 A still further object is to provide an improved process of the type characterized above in which the individual grains are all subjected to uniform and progressively increasing temperature up to the instant of pressure release.

35 Another object is to provide an improved process of the above type in which the conditions of temperature, pressure and time of exposure of the grains thereto can be controlled readily.

40 A still further object is to improve the quality and uniformity of puffed cereal products.

It has been found that the foregoing objects can be accomplished by continuously moving a stream of loose individual grains through an elongated confined pressure zone having at its outlet end an open discharge orifice large enough to permit the grains to pass freely therethrough, and by maintaining said zone under steam pressure which causes a high velocity current of steam to escape continuously through said orifice. The expression "loose individual grains" is here used to mean a freely moving stream of grains which are not packed tightly together, in differentiation from a packed or plugged conveying system through which a compacted mass of grain is forced. Such packing or plugging should be avoided because of the danger of physical distortion of and mechanical damage to the hot moist grains, in order to insure continuous movement of all grains at the desired rate with free access

of the steam to each grain, and in order to bring the grains to the outlet in loose condition for discharge from the pressure zone in the manner hereinafter described. To maintain the desired conditions, the conveyor system should not be filled to capacity; for example, good results are obtained when the per cent of fill is not more than 50% of capacity. Thus speed of travel of the stream of grain through the pressure zone can be regulated to predetermine the time of exposure of each grain to the steam pressure and temperature in said zone, and since the stream of grain moves continuously at the desired speed, all of the individual grains are subjected to uniform heating and cooking conditions and are brought to the same state as they reach the outlet end of said zone.

The grains reaching the vicinity of the orifice, being in loose freely moving condition, are picked up individually by the current of steam and conveyed freely through the orifice, i. e., without clogging the orifice and in most cases without any contact with its walls so that mechanical damage is minimized if not completely avoided. It will be seen that since the speed of movement of the grains through the orifice is very high in comparison with that of the stream of grain passing through the pressure zone, said stream is in effect attenuated as it passes through the orifice and hence the orifice can be much smaller than said stream. In many cases the orifice need be only somewhat larger than the maximum dimensions of the individual grains which are discharged one by one in a continuous stream at high velocity. If the rate of feed of the grain to the pressure zone is increased, however, it may be desirable to increase the size of the orifice sufficiently to permit several grains to pass through at one time without clogging. The size of the orifice therefore depends in part on the rate of feed of the grain; it should be proportioned in relation thereto so as to be only large enough to permit free passage of the grain in order to avoid undue consumption or waste of steam. By way of example, good results have been obtained with orifice diameters ranging from $\frac{1}{8}$ " to 1", the larger orifice sizes being used with relatively high rates of feed of the grain. Thus each individual grain passes freely through the orifice at the high velocity of the current of steam, and inasmuch as the distance to be traveled in passing through the orifice is small, the pressure on and in each grain is released practically instantaneously and a continuous stream of uniformly cooked and puffed grains is discharged from the orifice.

In practicing the above process, the steam pressure in the pressure zone should be maintained at a value such that the pressure drop through the orifice is sufficient to accomplish the desired puffing. The magnitude of the pressure drop required for this purpose may vary substantially and is not critical. At unduly high pressures (and correspondingly high temperatures) in the pressure zone, some of the grains will be overpuffed and shattered and may have a burned taste, while very low pressures do not produce satisfactory puffing. Within these limitations, however, a fairly wide range of pressures can be used satisfactorily. Moreover, at any pressure satisfactory for puffing, and with an orifice of restricted area as described above, the velocity of the current of steam passing through the orifice will be ample to release the pressure with great rapidity, the grains traveling from the pressure zone to a region of atmospheric pressure (a distance of say

1") in a small fraction of a second. As a general rule, the pressure may be somewhat less than that heretofore customary in grain puffing as indicated by the example set forth above; for example, a pressure in the range of 100-160 lbs./sq. in. will give satisfactory results in most cases. Using saturated steam, the corresponding temperature range will be about 340°-370° F.

Since the conditions of temperature and pressure are most critical in the immediate vicinity of the discharge orifice, the steam is preferably admitted to the pressure zone at its outlet end, and fills the zone so that the temperature of the grains is progressively increased as they move through the pressure zone to its outlet end. A suitable restricted steam outlet may be provided at or near the inlet end of the pressure zone so that in addition to the high velocity current of steam through the orifice, there is also a more gradual movement of steam back through the pressure zone countercurrent to the stream of grain passing therethrough.

Wetting of the surfaces of the grains by condensed moisture during their passage through either the pressure zone or the nozzle should also be avoided, as such wetting tends to cause the product to be wet and undersized. For this reason the quality of the steam at the orifice should not be less than about 100%, and if desired may be somewhat superheated. As the quality of the steam changes from wet saturated to dry saturated or superheated, there is a marked increase in the size of the puffs when other conditions remain constant. Excessive superheat, however, may cause the surfaces of the puffed grains to be rough and pitted and is preferably to be avoided in most cases. In the range of pressures and temperatures mentioned above, the degree of superheat preferably should not exceed 40-60°, best results being obtained in the range of 0-40° superheat. Also condensation of steam in the pressure zone can be minimized by warming or heating the walls of the zone and by preheating the grain itself before it enters the zone.

Preheating of the grain is desirable for the additional reason that it greatly increases the capacity of the apparatus without sudden or unduly prolonged exposure of the grain to high pressure and temperature. To avoid condensation, the temperature of the grain entering the pressure zone should not be less than about 190° F. and preferably it should be substantially higher to obtain the maximum benefit of preheating. However, excessive preheat will cause discoloration and a burned taste, and may result in shattered product. As a rule, 260° F. is regarded as a maximum preheat temperature for these reasons.

The accompanying drawing illustrates somewhat diagrammatically a suitable apparatus for carrying out the process described generally above, but it is to be understood that said drawing is by way of example only and is not to be taken as a definition of the limits of the invention, reference being had to the appended claims for this purpose.

In the form shown, the confined pressure zone is established and maintained in a plurality of cylindrical containers 1, here shown as five in number, which are disposed in parallel side by side relation and interconnected at alternate ends of the successive pairs as shown at 2. The grain to be puffed enters the inlet end of this apparatus through a feed conduit 3 and the stream of grain passes continuously through the series of containers to the outlet conduit 4 and orifice

5 at the end of the last container. Any suitable means can be used for moving the stream of grain through these containers, as by means of gravity feed or any suitable type of conveyor mechanism. For example, conventional screw conveyors can be employed as shown in the case of the first and last containers. Each of these conveyors comprises flights 6 mounted on an arbor 7, the arbor shaft 8 passing outwardly through the heads 9 at the ends of the container and through suitable pressure glands 10 which seal the containers against escape of steam therefrom. The ends of the shafts 8 can be mounted in any suitable bearings 11, and the several shafts can be driven in any suitable manner, preferably by any desired type of variable speed driving mechanism so that the time of passage of the grain through the pressure zone, and accordingly the time of exposure of the grain to the high temperatures and pressures maintained therein can be regulated. A series of containers 1 is preferred to a single container of equivalent length in order to facilitate the mounting of the arbor shafts and to avoid the necessity for intermediate bearings which might interfere with the free flow of the grain.

The pressure steam is supplied to the pressure zone at a point adjacent the outlet 4 in any suitable manner. As shown, a steam pipe 12 provided with a pressure control valve 13 is connected to the last container 1 near its outlet end, the steam thus admitted to the last container filling the entire series of containers with a steam atmosphere and also causing a high velocity current of steam to escape continuously through the outlet 4 and orifice 5. The size of the orifice determines the steam consumption of the equipment at any given pressure to be maintained. The inlet end of the first container 1 is also provided with a suitable steam exhaust, and as shown, an exhaust pipe 14 provided with a bleed valve 15 is connected to the grain inlet conduit 3.

Any suitable means can be employed for admitting the grain to the first container 1 in such a way as to prevent escape of steam from the container and loss of pressure in the pressure zone. Various known types of pressure locking feed valves can be used for this purpose. For purposes of illustration, the drawing shows a feed hopper 16 delivering grain through a suitable stop valve 17 to a feed chamber 18 from which the grain is delivered through a second stop valve 19 to the inlet conduit 3. For a purpose described hereinafter, the feed chamber 18 is provided with a steam inlet pipe 20 and a control valve 21 therein and with a steam exhaust pipe 22 having a control valve 23 therein.

In order to prevent condensation of steam on the walls of the several containers, they may be externally heated in any suitable manner as by means of steam jackets 24. As shown, the temperature of each jacket 24 can be individually controlled by means of a steam inlet pipe 25 having a suitable pressure control valve 26 therein, the steam exhausting from the jacket through an exhaust pipe 27, but if desired the jackets may be serially connected and controlled by a single pressure control valve.

In preparing the above equipment for use, steam is admitted to the jackets 24 to warm all of the container walls throughout the pressure zone. With the feed chamber 18 empty, the stop valve 19 is opened and the stop valve 17 closed, and the valve 21 is closed and the valve 23 opened. Steam is admitted to the containers through the control valve 13, the steam escaping

through the nozzle 5 and also passing back through the series of containers and escaping through the feeder exhaust valve 23. This warming operation is continued until there is no further condensation of moisture on the walls of the containers as indicated by the appearance of the exhaust steam discharged therefrom.

When the apparatus is ready for use, the feeder exhaust valve 23 is closed, the stop valve 19 is closed, and the stop valve 17 is opened to admit a measured amount of grain from the hopper 16 into the feed chamber 18. The stop valve 17 is then closed and the feeder inlet valve 21 is opened to build up a steam pressure in the feed chamber greater than the pressure on the nozzle 5. At this point the valve 21 is closed and the valve 19 is opened so that the charge of grain is discharged from the feed chamber through the feed conduit 3 into the end of the first container 1 where the grain is picked up by the conveyor 6. Successive charges of grain are thus introduced into the first container at a rate such as to supply a continuous stream of grain of the desired size to the nozzle 5.

As explained above, the size of the orifice opening at the nozzle 5 should be large enough to permit the stream of grain to pass freely therethrough at high velocity without clogging the orifice opening and without physical distortion or mechanical damage to the grains. As the rate of feed of the grain is increased, therefore, the size of the orifice opening must also be increased and the steam consumption is increased correspondingly. The proper proportioning of these factors depends on the desired capacity of the apparatus. Within reasonable limits, the rate of feed of the grain can be varied by regulating the speed of rotation of the screw conveyor to permit variations in production without change of the nozzle 5.

The nozzle and orifice may have any suitable shape, good results having been obtained with nozzles of Venturi shape, with simple orifice plates, and with a nozzle of the form shown in the drawing having a tapering passage leading to a relatively small orifice opening. Any other desired type of nozzle or orifice can be employed.

In operation, the bleed valve 15 permits a continuous gradual flow of steam from the inlet pipe 12 through the series of containers to the grain feed pipe 3, the steam thus moving countercurrently to the stream of grain fed by the conveyor 6. Accordingly the temperature of the grain is progressively increased as it moves through the pressure zone to its outlet end, and as long as the rate of feed is maintained constant, each individual grain is subjected to uniform heating and cooking conditions during its passage through the pressure zone. Preheating of the grain as described above enables the length of the pressure zone to be decreased and the capacity of the equipment to be greatly increased. Furthermore, the preheating of the grain avoids condensation of moisture on its surfaces at the inlet end of the pressure zone and avoids difficulties which would be encountered in feeding cold wet grain due to packing of such grain in the screw conveyors. Limitation of the percentage of fill of the conveyor system is also desirable to prevent packing, insure continuous uniform feed of the grain through the pressure zone, and maintain the individual grains in loose condition so that they can be picked up readily and carried through the nozzle 5 by the steam current.

The following is an example of processes embodying the invention as practiced in apparatus of the type described above and illustrated in the drawings:

Amber durum wheat having a bulk density of about 46 lbs. per cubic foot and a moisture content of about 9.5%, the bran coat being largely removed, was preheated to a temperature of 230° F. and introduced into the pressure zone through the hopper 16 and feed chamber 18 as described above. The walls of the zone were heated by maintaining a steam pressure of 240 lbs./sq. in. (gauge) in the jackets 24. The rate of feed of the grain was 1800 lbs. per hour, and the speed of the conveyors was adjusted to provide a hold-up time in the pressure zone of 2½ minutes.

Dry saturated steam at a pressure of 240 lbs./sq. in. was supplied to the pipe 12 and the reducing valve 13 was set to maintain a pressure in the pressure zone and on the nozzle orifice of approximately 140 lbs./sq. in. (gauge), the temperature being 375° F. The diameter of the orifice opening was $\frac{3}{8}$ ". Under these conditions a continuous stream of individual puffed grains issued at high velocity from the orifice, the grains being uniformly cooked and puffed and constituting a puffed wheat product of uniformly high quality having a moisture content of 7% and a bulk density of only 4 lbs. per cubic foot.

It will be understood that the invention is not restricted to the details of the foregoing description and example, and that various changes may be made in the practical operation of the process without departing from the spirit of the invention. Also the apparatus illustrated in the drawing is by way of example only, and the process can be carried out in various other forms of apparatus capable of producing equivalent results, as will be apparent to those skilled in the art. Accordingly reference should be had to the appended claims for a definition of the limits of the invention.

What is claimed is:

1. A process for puffing cereal grains which comprises maintaining steam pressure in an elongated confined zone having an orifice opening at its outlet end through which a high velocity current of steam continuously discharges, moving a stream of loose individual grains continuously through the steam atmosphere in said zone to said outlet end, and conveying the loose grains as they arrive at said outlet end through said orifice in said current of steam whereby a continuous stream of individual puffed grains is discharged from said zone.

2. The process defined in claim 1, the quality of the steam leaving said zone through said orifice ranging from substantially dry saturated steam to about 60° superheat.

3. The process defined in claim 1, the steam pressure at the outlet end of said zone ranging from about 100 lbs./sq. in. to about 160 lbs./sq. in.

4. The process defined in claim 1, said grain being preheated to a temperature in the range of 190-260° F. before entering said zone.

5. A process for puffing cereal grains which comprises continuously moving a stream of loose individual grains through an elongated confined zone having a steam exhaust passage adjacent its inlet end and a discharge orifice adjacent its outlet end while admitting steam under pressure to said zone adjacent said orifice, thereby filling said zone with an atmosphere of steam under pressure moving countercurrently to said stream of grain and causing a high velocity current of

steam to escape continuously through said orifice, and moving said stream of grain into the path of said current of steam whereby individual loose grains are conveyed through said orifice at substantially the same velocity as that of said current.

6. The process defined in claim 5, the steam pressure in the outlet end of said zone being in the range of 100-160 lbs./sq. in.

7. The process defined in claim 6, the quality of the steam admitted to said zone ranging from the substantially dry saturated condition to about 60° superheat.

8. The process defined in claim 7, including the step of preheating the grain to a temperature of about 190-260° F. before admitting it to said zone.

9. The process defined in claim 8, wherein the walls of said zone are heated to prevent substantial condensation thereon.

10. A process for puffing cereal grains which comprises continuously moving loose individual grains through an elongated confined zone having at its outlet end an open discharge orifice larger than the maximum dimensions of the individual grains, and maintaining an atmosphere of steam under pressure in said zone and a high velocity current of steam through said orifice by continuously admitting steam to said zone, the loose individual grains reaching the outlet end of said zone being moved into the path of said current and conveyed freely through said orifice thereby.

11. The process defined in claim 10, the steam pressure at the outlet end of said zone being in the approximate range of 100-160 lbs./sq. in.

12. The process defined in claim 11, the quality of the steam entering said orifice ranging from substantially dry saturated steam to about 60° superheat and the grain being preheated before entering said zone, whereby condensation of moisture on the grain is substantially prevented.

13. A process for puffing cereal grains which comprises the steps of preheating whole grains containing about 6-10% moisture to a temperature in the range of 190-260° F., continuously moving a stream of loose individual preheated grains through an elongated confined zone having at its outlet end an open discharge orifice larger than the maximum dimensions of the individual grains, and continuously admitting steam to said zone adjacent said orifice at a pressure in the approximate range of 100-160 lbs./sq. in. and of a quality ranging from substantially dry saturated steam to about 60° superheat, thereby maintaining a high velocity current of steam through said orifice, the loose individual grains reaching the outlet end of said zone being moved into the path of said current and conveyed freely through said orifice thereby.
